UNITED STATES PATENT OFFICE.

CLARENCE C. JENKINS, OF BROOKLYN, NEW YORK.

DISINFECTANT-BLOCK.

SPECIFICATION forming part of Letters Patent No. 739,317, dated September 22, 1903.

Application filed March 7, 1903. Serial No. 146,605. (No model.)

To all whom it may concern:

Be it known that I, CLARENCE C. JENKINS, a citizen of the United States, residing at Brooklyn, in the county of Kings and State of New York, have invented certain new and useful Improvements in Disinfectant-Blocks; and I do hereby declare the following to be a full, clear, and exact description of the invention, such as will enable others skilled in the art to 5 o which it appertains to make and use the same.

This invention relates to disinfectant-blocks; and it consists, essentially, of any suitable disinfectant compound molded into blocks or cakes and provided with suitable 15 grooves in its under surface to permit the free passage of water.

The principal object of the invention is to provide a convenient form of block or cake of the character mentioned, to be placed in 20 a urinal-basin directly over the water-outlet, which will permit the water to pass freely underneath and about the block to insure disinfection.

In the drawings, Figure 1 is a perspective 25 view of my improved disinfectant-block; Fig. 2, a bottom plan view, and Fig. 3 a vertical sectional view.

Referring to the several views, the letter *a* indicates a block of any suitable disinfectant 30 compound, molded into a suitable shape, preferably with an upwardly-flaring outer side surface and flat top, as shown. The under side of the block is provided with grooves or cut-out portions *b b*, preferably crossing each 35 other at right angles, as clearly shown in Fig.

2. The purpose of these grooves is to provide for the free passage of the water when

the block is placed in the basin. The block may be, if desired, provided with a central water-passage *c*, intersecting the grooves at 40 their junction. To insure perfect disinfection when long basins are used, a block should be placed every two or three feet.

While it is preferred to form the grooves in the under side of the block in the shape of a 45 cross, it will be evident that they may be formed in any manner which will permit the water to pass freely beneath and around the block to the outlet.

Having thus fully described my invention, 50 what I claim, and desire to secure by Letters Patent, is—

1. As an article of manufacture, a block or cake of disinfectant material, having its bottom or under surface provided with one or 55 more water-passages.

2. As an article of manufacture, for disinfecting urinal and other basins, a block or cake of disinfectant material having its bottom or under side provided with crossed wa- 60 ter-passages for the flow of water beneath the block.

3. As an article of manufacture, a block or cake of disinfectant material, having its bottom or under side provided with water-pas- 65 sages crossing each other at right angles, and a central perforation intersecting the point of juncture of the grooves.

In testimony whereof I affix my signature in the presence of two witnesses.

CLARENCE C. JENKINS.
